UNITED STATES PATENT OFFICE.

FREDERICK MONTILIOUS WHITTEMORE, OF NEW YORK, N. Y.

INTERCHANGEABLE-LETTER SIGN.

1,296,246.

Specification of Letters Patent.

Patented Mar. 4, 1919.

Application filed August 14, 1917. Serial No. 186,138.

To all whom it may concern:

Be it known that I, FREDERICK M. WHITTEMORE, a citizen of the United States, residing at New York, in the county of New York and State of New York, have invented certain new and useful Improvements in Interchangeable-Letter Signs; and I do declare the following to be a full, clear, and exact description of the invention, such as will enable others skilled in the art to which it appertains to make and use the same.

This invention relates generally to advertising devices, but more particularly to certain new and useful improvements in signs.

The primary object of the invention is to provide an interchangeable letter sign, the interchangeable letters of which are so constructed and arranged that they may be easily seen and distinguished in the daytime, and which can be effectively illuminated so as to be distinguished at night.

Another object of the invention is to provide a sign of this character which is so constructed that the cost of illuminating it at night will be considerably less than those now in common use.

A further object of the invention is to provide a sign of this description which will be of extremely simple, strong, durable and inexpensive construction, one which will be efficient and reliable in operation, and well adapted to the purpose for which it is designed.

With these and numerous other objects in view, the invention consists of certain novel features of construction and combination and arrangement of parts as will be hereinafter fully described and claimed.

In the accompanying drawings forming a part of the application, and in which similar reference characters are used to designate like parts throughout the several views;

Figure 1 is a front view of a sign made up of four interchangeable letters constructed in accordance with this invention;

Fig. 2 is a front view of one of the interchangeable letter signs on an enlarged scale;

Fig. 3 is a vertical sectional view taken on the plane indicated by the line 3—3 of Fig. 2;

Fig. 4 is a vertical sectional view taken on the plane indicated by the line 4—4 of Fig. 3;

Fig. 5 is a horizontal sectional view taken

on the plane of the line 5—5 of Figs. 2 and 4; and,

Fig. 6 is a front elevation of a portion of the apron carrying the letters and figures. 60

Referring more particularly to the drawings, the numeral 1 designates a casing which is preferably made of metal and which is comparatively shallow and of substantially rectangular shape in front view. 65 The back of the casing 1 is provided with suitable apertured ears 2 by which it may be secured to a support. The front or open side of the casing is provided with a removable plate 3 which has arranged therein a substantially square-shaped opening 4. The opening 4 occupies the greater portion of the plate 3 and is approximately the size of the letters and figures of the sign. The plate 3 is flared inwardly at 5 at the edges 70 of the opening 4 as clearly shown in Figs. 3 and 5 of the drawings.

Fixedly secured within the casing 1 and extending transversely of the same is a stationary member or plate 6. This plate 6 is 80 disposed directly behind the opening 4 and near the inner edges of the flared portions 5 of said opening. Arranged in the plate 6 is a set of perforations 7. These perforations 7 occupy a space slightly smaller than the opening 4 in the plate 3, and are capable of being selectively displayed in a plurality of combinations to form one at a time the individual letters of the alphabet and the ten numerical digits. Whenever the word 85

letter is used hereinafter, its broadest definition is intended, viz., "a mark or character used to represent a sound or articulation of human speech," thus including numerals. Arranged in the openings 7 are lenses 8. 90 These lenses 8 are constructed somewhat similar to that shown in Patent No. 1,190,498 to Harry S. Williams, and have their rear faces formed with a number of parallel steps 9 which are designed to bend the rays 100 of light and to project them through the lenses. The source of light consists of a single electric bulb 10 which is fixed to the back of the casing 1 near the lower end of the same in any convenient manner. By the 105 use of the style of lenses above described and by having the interior of the casing 1, especially the inner side of the back of the same brightly painted, the rays of light will be so reflected that approximately an equal 110 amount will pass through each of the lenses.

Revolutely mounted between the side walls

of the casing 1 is a pair of rollers 11 and 12, the roller 11 being disposed at the upper end of the casing while the roller 12 is disposed at the lower end. The shafts of the 5 rollers 11 and 12 have ends projected through one of the side walls of the casing and suitably shaped to receive a crank arm 13 whereby said rollers may be revolved. It 10 is to be understood, however, that other means for turning the rollers may be employed.

Disposed upon the rollers 11 and 12 and stretched between the same is an apron 14. This apron 14 may be made of any suitable 15 material but is preferably made of very thin sheet or strip aluminum. The portion of the apron 14 which is disposed between the rollers passes around the ends of the plate 6 over the same. To maintain the 20 apron at all times in superposed relation with respect to the plates 6, the latter is provided with suitable guides 15 which hook around the edges of the apron and prevent it from bulging outwardly.

25 As clearly shown in Fig. 6 of the drawings, the apron 14 is provided with a plurality of sets of perforations forming all of the letters of the alphabet and all of the numerical digits. The apron 14 covers 30 the perforations in the plate 6 with the exception of those which register with the perforations 16, and obviously when the sign is illuminated only a single character can be seen. The exterior side or face of the apron 35 14 is painted or otherwise provided with means for indicating the characters formed by the different sets of perforations. This is clearly illustrated in Figs. 2 and 6 of the drawings where the letters formed by the 40 perforations 16 are outlined by heavy lines.

In Fig. 1 of the drawings a four letter sign is shown. In this case four of the casings 1 are secured to a pair of upright posts *a* and the aprons 14 of the various 45 casings are turned or wound from one roller to the other until the proper letters appear opposite the openings 4. In the night when the lamps of the various casings are lit, the rays of light from the same will pass through 50 the registering openings in the relatively movable members of the casing and the letters can be plainly distinguished. In the daytime the letters can be just as readily distinguished by the heavy lines which outline them. It is obvious that at any time 55 the aprons may be shifted so that any other word may be spelled.

From the foregoing description, taken in

connection with the accompanying drawings, the construction, use and operation of 60 the device will be readily understood without a more extended explanation.

As various changes in form, proportion, and in the minor details of construction may be resorted to without departing from the 65 spirit of this invention, it is to be understood that I do not wish to be limited to the construction herein shown and described other than as claimed.

I claim:

70 1. In an interchangeable letter sign, a casing having an opening in its front, a lamp in said casing, a plate in said casing between said lamp and said opening and provided with a series of rows of openings, 75 said series registering with said opening of the casing, and an apron extending between the opening of said casing and the openings of said plate and being movable relative to said casing and plate and provided 80 with sets of openings each set of which forms a letter that is different from the letter formed by other of said sets of openings, the openings of each of said sets being adapted to register with and thereby select 85 a corresponding set of the openings of said plate, said apron hiding the openings of said plate which are not in registry with a set of its own openings.

90 2. In an interchangeable letter sign, a casing having an opening in its front, a lamp in said casing, a plate in said casing between said lamp and said opening and provided with a series of rows of openings, 95 said series registering with said opening of the casing, and an apron extending between the opening of said casing and the openings of said plate and being movable relative to said casing and plate and provided with different opaque letters and with light 100 openings within the confines of said letters and themselves combining to form such letters, the openings of each of said sets being adapted to register with and thereby select 105 a corresponding set of the openings of said plate, said apron hiding the openings of said plate which are not in registry with a set of its own openings.

110 In testimony whereof I have hereunto set my hand in the presence of two subscribing witnesses.

FREDERICK MONTILIOUS WHITTEMORE.
